UNITED STATES PATENT OFFICE.

GEORGE S. WITHAM, JR., OF HUDSON FALLS, NEW YORK.

APPARATUS FOR CONTROLLING THE DRYING OPERATION IN PAPER MACHINES.

Application filed April 2, 1928. Serial No. 266,777.

This invention relates to apparatus for controlling the drying operation in paper machines and more in particular to apparatus for controlling the moisture content of 5 the paper at a certain stage of its manufacture.

The invention is closely related to apparatus of the type disclosed in my Patents 10 1,626,060, 1,646,515 and 1,646,516 and has for its general object a simplification of structure.

For a full understanding of the invention, reference is made to the accompanying drawings, wherein:

15 Fig. 1 is a fragmentary side view of apparatus embodying the invention;

Fig. 2 is an enlarged view of parts shown in Fig. 1;

20 Fig. 3 is a sectional view taken on line 3—3, Fig. 2.

Having reference to Fig. 1, 10 are the drying rolls of a typical installation consisting of two or more rows of drying drums or cylinders in super position. The web 11 of the 25 paper is carried around the drying cylinders 10 in the usual way and the felt roll 12 with the felt 13 passing over the drying cylinders in superposition on the web of paper also constitutes part of a usual form of 30 paper machines.

In the space between the drying cylinders 10, below the felt roll 13 is disposed a metal blade 14 generally referred to in the 35 trade as a "doctor", the lower edge of which is in intimate contact with the roller cylinder 10. The doctor, which serves the emergency purpose of loosening and lifting the web of paper free from the cylinder is also a standard part of an equipment of this 40 type.

45 The invention consists in an arrangement whereby the parts referred to are utilized to form a collector box for directing a gas or air into contact with a surface portion of the web of paper, at the exclusion of the atmosphere normally surrounding the paper.

Having special reference to Figs. 2 and 3, the space between the doctor, the lower drying cylinder 10, the web of paper 11 on the 50 upper left-hand drying cylinder 10, the felt roll 12 and the felt 13 is converted into a collector box for the passage of air in contact with the portion of the paper web passing continuously past the space. As seen 55 from Fig. 2, between the upper edge of the doctor blade 14 and the felt roll there is

ordinarily a large gap. In order to close this gap, a sealing member 16 of any suitable flexible material is attached to the doctor 14 along its whole upper edge and so 60 disposed as to ride against the felt roll 13, as indicated. While there are many materials available for the purpose of sealing the gap, I prefer at present rubber belting or the like.

To carry out the object of the invention, air is blown into the collector space referred to, to thereby take up the moisture given off by the paper and the moisture-charged air is then passed to a moisture-responsive device. As indicated in dotted lines in Fig. 3, air is preferably prepared or conditioned in a conditioning apparatus 17 and then passed by a blower 23 or the like into the space mentioned. With the nozzle 18 is preferably associated a board 19 for roughly sealing the space adjacent to the nozzle against influx of air from the body of air surrounding the machine. It is not practically possible and not necessary to entirely close off communication between the collector space and the outside, leakage of air into the collector space being avoided by producing a sufficient positive pressure at the nozzle end.

80 Into the end of the collector space opposite to the nozzle 18, I place a pipe 21 for passing a sampling stream of the moisture-charged air to a moisture sensitive element 22 actuating an indicating device 24 or a recording device or a regulating device as 90 may be desired. For practical reasons I prefer to produce a continuous flow of a sampling stream by means of a suction blower 23.

95 The operation and its significance are as follows:

The paper manufactured is passed over the drying cylinders. The surface portion of the web forming part of the collector space described has a definitely limited area. The 100 amount of moisture given off in a unit of time by this changing surface of constant area is therefore a measure of the moisture content of the web of paper at the particular point of travel, assuming that the other conditions 105 of operation are fairly constant.

By preparing air of constant temperature and constant relative humidity, i. e. of constant properties as to temperature and humidity for passage through the collector 110 space, the moisture content of the air passing out of the latter is a reliable criterion

of the moisture content of the web of paper as it passes the space. By directing this air or a representative sample thereof against a moisture-responsive device, as for instance 5 against a wet bulb thermometer, the variations in the moisture content can be indicated, recorded or otherwise utilized for the control of the drying operation.

Provisions may be made to shield the collector space against the effects of heat from 10 the lower cylinder 10 or other parts other than the web, but I have found that these effects do not introduce any appreciable errors, but on the other hand, have beneficial 15 action in that they cause a rise of the temperature of the air passing through the collector space and thereby reduce or even prevent condensation or sweating.

In some instances I find it desirable or 20 even practically necessary to at least partly close up the end of the space where the suction nozzle 18 is located in order to obtain the proper amount of positive pressure in the collector space.

25 In the foregoing I have made reference only to air as a medium for the absorption of moisture, and more in particular to conditioned air. It is understood the invention is not affected by the character of the gaseous medium.

For the sake of brevity in the claims, the word "doctor" designates a blade so positioned in contact with a roll adjacent to the line at which a web of paper passing over 35 the roll normally draws away from the latter, as to immediately lift the paper from the roll in case the paper should stick to the roll beyond the normal line of separation.

40 I claim:

1. In apparatus of the character described, having two rows of drying rolls in staggered relation, wherein a web of paper passes alternately over a roll of each row, a felt roll between adjoining rolls of one row and opposite a roll of the other row and a doctor disposed between the felt roll and the last mentioned roll and bearing on the latter, the combination with the doctor, of a sheet of 45 flexible material attached to the doctor and bearing upon the felt roll, whereby the doctor and the sheet form a partition connecting the felt roll and the drying roll upon which the doctor bears.

50 2. In apparatus of the character described,

having two rows of drying rolls in staggered relation, the combination with two adjoining rolls of one row, a felt roll disposed between the adjoining rolls carrying a belt for movement over the adjoining rolls, the drying roll 60 of the other row, disposed intermediate the said adjoining rolls and a doctor disposed between the felt roll and the said roll of the other row and bearing upon the latter, of a sheet of flexible material attached to the doctor and bearing upon the felt roll, whereby the doctor and the sheet form a partition substantially coextensive with the rolls.

3. In apparatus of the character described, having two rows of drying rolls in staggered 65 relation, wherein a web of paper passes alternately over a roll of each row, a felt roll between adjoining rolls of one row carrying a felt passing over said adjoining rolls, a doctor disposed between the felt roll and the adjacent roll of the other row bearing upon the latter, the combination with the doctor, of a sheet of flexible material attached to the doctor and bearing upon the felt roll, whereby the doctor and the sheet form a partition connecting the felt roll and the drying roll upon which the latter bears, and defining with the last mentioned drying roll, the felt on the felt roll and the web of paper a conduit for a gas, means for passing a gas 75 into one end of said conduit and means for withdrawing gas from the other end of said conduit.

4. In apparatus of the character described, having two rows of drying rolls in staggered 80 relation, wherein a web of paper passing alternately over rolls of the two rows, in conjunction with the rolls defines trough-like spaces intermediate the ends of the latter, a felt roller disposed between two rolls of one 85 row, carrying a felt passing over the two rolls and a doctor disposed between the felt roll and the opposite drying roll of the other row and bearing upon the latter, the combination with the doctor, of a sheet of flexible material attached to the latter and disposed to bear upon the felt roll, the doctor and the sheet forming a partition for separating the trough-like space into two sections and means for passing a gas through one of the said sections to absorb moisture from the web of paper which forms a part of the conduit.

In testimony whereof I affix my signature.

GEORGE S. WITHAM, JR.
